Attorney

UNITED STATES PATENT OFFICE.

GEORGE N. BARCUS, OF ANDREWS, INDIANA.

SPARK PLUG.

Application filed June 20, 1927. Serial No. 200,150.

My invention relates to a spark plug and process of manufacturing the same and it is an object of the invention to provide a plug in which pressure differences on the 5 gaskets are greatly reduced thus proportionately reducing the cause of leakage, and a further object of the invention is in manufacturing to reduce the breakage of insulators and to prevent localized stresses on 10 said insulators, all as will be hereinafter more fully described and claimed.

Referring to the accompanying drawings which are made a part hereof and on which similar reference characters indicate similar 15 parts,

Figure 1 is a side elevation of the spark plug constructed in accordance with my invention,

Figure 2, a part side elevational, part sectional view showing in outline the rotating spindles for compressing parts of the plug in assembling, and

Figure 3, a fragmentary detail section of the sleeve shown in Fig. 2 illustrating the 20 method in which the same is rolled or shrunk onto the body member.

In the drawings reference character 10 indicates the body member or shell of a 25 spark plug having its lower end threaded 30 for engagement with the cylinder wall of an internal combustion engine and having an annular flange 11 adapted to seat on such cylinder wall for limiting the movement of the body into the cylinder wall. The upper 35 end of the body 10 is provided with an inclined or flared end portion 12 which forms a seat for an insulator 13 of conventional construction. The insulator 13 is provided with a relatively short tapered upper end 40 portion and a slightly longer tapered lower end portion between which is disposed a substantially cylindrical intermediate portion having upper and lower inclined shoulders 14 and 15. The insulator 13 is also 45 provided with a central electrode of conventional construction which may be held in place in the insulator by lock-nuts 16 or in any other well known manner.

Means is provided for binding the insulator tightly against the end of the body member or shell 10 and such means comprises a shell or sleeve 17 having a shoulder 18 formed complementary to the shoulder 14 of the insulator and provided with a lower 50 end 19 of a reduced thickness so that it may be easily rolled or spun into an annular

channel or slot 20 on the body member or shell 10.

A gasket 21 is disposed between the shoulders 14 and 15 and the cooperating abutting 55 surfaces in order to form a gas tight joint when the parts are in assembled relation. The bottom of the annular channel or slot 20 of the body 10 is preferably knurled at 60 22 so that when the sleeve and body are 65 pressed together they will be secured in fixed relation to each other so that upon rotation of the sleeve 17 by means of a wrench or other suitable tool the body 10 will also be 70 rotated.

In assembling the parts of the plug, the insulator 13 is provided with a gasket at 75 each side of its enlarged cylindrical portion, the lower gasket serving to seal the joint between the upper inclined or flared end of 80 the body 10 and the shoulder 15 of the insulator, and the upper gasket being adapted to seal the joint between the complementary portion of the sleeve or shell 17 and the inclined portion 14 of the insulator. The parts 85 are placed between rotating spindles 23 and 24, which are shown in dotted lines in Fig. 2, and force is applied for pressing the sleeve 17 upon the body 10 of the plug for uniformly compressing the gaskets 21 after which a 90 roller 25, shown in dotted lines in Fig. 3, is applied against the thin lower portion of the neck or reduced lower end of the sleeve 17 by means of which the said sleeve is spun or rolled into the annular channel or slot 95 20 around the body of the plug. This rolling operation causes the thin portion of the sleeve or thread as it enters the channel 20 to become elongated and fit tightly between the sides of the channel or slot which causes 100 a tight joint with the interior of the sleeve snugly engaging the knurled surface 22. Pressure applied for forcing the sleeve or shell 17 upon the body 10 is only in an axial direction and the insulator is held in place 105 solely by such axial pressure while at the same time the rolling is accomplished in spaced relation to the enlarged portion of the insulator, thereby practically eliminating the breakage of insulators in manufacture as well as the elimination of localized stresses 110 on the insulator while at the same time the gaskets are subjected to sufficient pressure so that there is practically no chance for leakage around the same.

It will be obvious to those skilled in the art that various changes may be made in my

device without departing from the spirit of my invention, and I, therefore, do not limit myself to what is shown in the drawings and described in the specification, but 5 only as set forth in the appended claims.

Having thus fully described my said invention, what I claim as new and desire to secure by Letters Patent, is:

1. A spark plug comprising a body having 10 an inclined upper extremity, an external annular channel below said extremity, a gasket resting on the extremity of said body, an insulator having an enlarged portion resting on said gasket, a gasket disposed on the 15 opposite side of the enlarged portion of the insulator, and a sleeve having an internal flange resting on said last mentioned gasket and having its opposite end spun into said annular channel on said body, substantially 20 as set forth.

2. The process of making a spark plug comprising telescoping a sleeve over the body of a plug, to compress an insulator therebetween, pressing said parts together in an 25 axial direction, and spinning the inner end of the sleeve tightly into engagement with the body of the plug, substantially as set forth.

3. A spark plug comprising a body having

one end threaded for engagement with a cylinder wall and having its other end inclined for engagement with a gasket, a channel formed about said body, an insulator resting on the upper end of said body, a sleeve engaging said insulator and having a reduced portion fitting snugly about said body, substantially as set forth.

4. The process of making a spark plug comprising telescoping a sleeve over a body of the plug, with an insulator therebetween, pressing said body and sleeve together in an axial direction and rolling the telescoped end of the sleeve tightly into engagement with said body, substantially as set forth.

5. A spark plug comprising a body having 45 its lower end portion formed for engagement with a cylinder wall, an insulator extending through said body, a sleeve engaging said insulator and secured on said body, said body being provided with an annular reduced knurled portion, said sleeve having a reduced annular portion disposed in said annular knurled portion, substantially as set forth.

In witness whereof, I have hereunto set my hand at Andrews, Indiana this 25th day 50 of May, A. D. nineteen hundred and twenty-seven.

GEORGE N. BARCUS.
